UNITED STATES PATENT OFFICE.

CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

SHOCKING-MACHINE.

1,226,373.

Specification of Letters Patent.

Patented May 15, 1917.

Application filed November 17, 1913. Serial No. 801,525.

To all whom it may concern:

Be it known that I, CLEMMA R. RANEY, a citizen of the United States, residing at Chicago, in the county of Cook and State of Illinois, have invented certain new and useful Improvements in Shocking-Machines, of which the following is a full, clear, and exact specification.

My invention relates to shocking machines.

10 In shockers of the type employing a swinging sheaf delivery member, wherein the sheaf delivery member is pivoted on the shocker frame and swings back and forth from sheaf receiving position beneath the binder deck to sheaf delivery position over the shocker cradle, it has been found that the sheaf delivery member, after it passes over its center in its backward movement, is accelerated or speeded up by the pull of 15 gravity to such a degree that it has a tendency to rebound when it strikes its support beneath the binder deck, with the result of seriously interfering with the operation of the shocker due to the displacement of the 20 fork when the next sheaf is discharged. Further, there has been an undue amount of wear and tear upon the machine due to the continued hammering of the sheaf delivery member against its support.

25 My invention has for its object to eliminate this objectionable rebounding or hammering of the shocker sheaf delivery member as the latter returns to its sheaf receiving position after the delivery of a sheaf.

30 I attain this object by providing retarding means operatively connected to the sheaf delivery member and a source of power operating at a constant speed, whereby, as the sheaf delivery member, in passing over its 35 center, is attracted by the pull of gravity, this member is automatically connected to mechanism moving at a slower, constant speed, thus eliminating any tendency to increase of speed due to the pull of gravity.

40 In the accompanying drawings I have shown one form which my invention may assume in practice. It is to be understood, however, that the form shown herein for purposes of illustration may be modified 45 without departing from the spirit of the invention.

In these drawings:

Figure 1 is a side elevation of the shocker equipped with my improvement;

Fig. 2 is a top plan view of a portion of 55 the operating mechanism;

Fig. 3 is a detail view of the clutch mechanism partially in transverse section;

Fig. 4 is a longitudinal section of the 60 clutch mechanism.

The shocker illustrated herein is of the type described and claimed in my copending application, Serial No. 573,106, filed July 21, 1910. This shocker comprises a main frame 1, having a transversely disposed operating shaft 2 journaled thereon, upon which is fixed a sheaf delivery member 3, shown in the form of a fork, movable back and forth in a vertical plane with the shaft 2 from the dotted line or sheaf receiving position shown in Fig. 1, wherein it rests on a support 4 carried on the binder frame (not shown) to the full line or sheaf delivery position shown in that figure; the shaft 2 being carried on the upper part of 70 the frame and operatively connected to a suitable, continuously operating source of power disposed beneath the same, such as a shaft 5, through a longitudinally disposed chain 6, a transverse shaft 7, a sprocket 8 carried on said shaft, and a resilient pitman connection 9 operatively connected between the shafts 2 and 7, and being controlled by means of a longitudinally disposed rocking trip arm 10, operated by the sheaves as they 75 are discharged from the binder deck and having a finger 11 engaging the clutch finger of a clutch 12 carried on the shaft 7 and adapted to be operatively connected to the constantly rotating chain and sprocket connection to throw the fork 3 into operation 80 when the trip 10 is actuated by a sheaf engaging therewith.

Associated with this sheaf delivery member or fork 3 are means for cushioning the 95 fork 3 when it reaches its dotted line or sheaf delivery position over the shocker cradle, and at the same time imparting a quick return movement to the latter to disengage the same from the delivered sheaf. These 100 means comprise a laterally extending arm 13 fixed on the shaft 2 at 14 and engaging a second arm 15 rotatably mounted beside it on the shaft 2 and adapted to abut against

a coiled spring 16 to place the same under tension as the fork 3 moves to sheaf delivering position, thus cushioning the blow of the fork and storing power in the spring, 5 which, after the fork has completed its travel, acts to start the same backward with a quick movement, separating the same from the delivered sheaf. As shown, the spring 16 is coiled around an arcuate rod 17, fixed 10 to the end of the movable arm 15, and extends between the arm 15 and a fixed abutment or bracket 18, carried on the frame 1, through which moves the free end of the rod 17 within the limits prescribed by the 15 spring 16 and a pin 19.

Coöperating with the fork 3, and cushioning means therefor just described, is my improved retarding mechanism for the fork. This mechanism, as shown in Figs. 3 and 4, 20 includes a sprocket 20 continuously driven by the chain 6 at the same or greater speed than the fork in the first stages of its rearward movement. This sprocket is rotatably mounted in the plane of the sprocket 8 and 25 above the same on a sleeve 21 fixed on the shaft 2 and, as shown, is provided with a serrated or toothed inner surface or periphery 22 adapted to be engaged by a pawl 23 pivotally mounted on a pin 24 carried on 30 the arm 13 and rotatable therewith; a spring 25 being provided therefor which encircles the pin 24 and is operatively connected at its ends to both the pawl 23 and the arm 13 in such a manner that it normally holds the 35 pawl in engagement with the teeth on the inner periphery of the sprocket 20 and locks the fork 3 to this constantly rotating sprocket when, as the arm 13 is rotated in a clockwise direction, the speed of movement 40 of the fork 3 tends to exceed the speed of the sprocket.

The operation of the construction shown is as follows: Assuming that the fork 3 is in the full line position shown in Fig. 1, upon 45 the return of the same to its dotted line or sheaf receiving position, due to the use of the yielding or resilient pitman drive, there would obviously be a tendency for the fork to accelerate or speed up after it has passed 50 its vertical position, with the result that the tined end of the fork 3 would strike its support 4 with a heavy blow, causing the rebound of the fork. By the provision of my improved retarding mechanism it is to be 55 noted that as the fork moves past its vertical position, the pawl 23 remains in engagement with the serrated inner surface of the sprocket 20 in such a manner as to connect the fork with the constantly rotating power 60 connection 5 through the chain 6, and thus remove any tendency for the fork to speed up, the fork, instead, being lowered from its vertical to its prostrate or sheaf receiving position at a constant speed. Obviously,

when the next sheaf is ejected from the 65 binder and strikes the trip 10, the fork 3 will again be operated through the pitman connection 9 upon actuation of the clutch 12 by the trip, the fork being freely movable 70 backward about its pivot to sheaf delivery position as the pawl 23 then runs freely over the serrated inner surface of the sprocket 20 in the reverse direction from that just described.

While I have in this application described 75 one specific form of my invention with a view to disclosing the same in the manner prescribed by the statutes, it is, of course, to be understood that the form shown herein may be modified without departing from the 80 spirit of my invention.

What I claim as my invention, and desire to secure by Letters Patent, is:

1. In a shocking machine, a frame, sheaf delivery mechanism including a movable 85 sheaf delivery member intermittently engageable with said frame, and means including a constantly rotating drive member engageable with said sheaf delivery member during a portion of the cycle of movement 90 thereof for preventing hammering of said member upon said frame.

2. In a shocking machine, a frame, sheaf delivery mechanism including a sheaf delivery member movable during a portion of its movement independently of its driving mechanism into engagement with said frame, and means for controlling the speed 95 of said member during such independent movement.

3. In a shocking machine, a frame, a sheaf delivery member pivoted thereon, means whereby said member is normally caused to move at a variable speed, supplemental constant speed mechanism, and means for automatically connecting said member thereto during a portion of its movement.

4. In a shocking machine, a frame, a sheaf delivery member pivoted thereon, operating mechanism for said member with respect to 110 which the latter may move independently during a portion of its movement, and means for maintaining said member at a constant speed during such independent movement.

5. In a shocking machine, a frame, a sheaf delivery member pivoted thereon and movable in one direction of rotation over its center into engagement with said frame, operating mechanism for driving said member over its center, and means for preventing acceleration of said member as it moves downward into engagement with said frame.

6. In a shocking machine, a frame, a sheaf delivery member pivoted thereon movable in a substantially upright plane into engagement with said frame, operating mechanism for driving said member over its center, and

means thrown into engagement with said member as the same moves downward for eliminating acceleration thereof into engagement with said frame.

5 7. In a shocking machine, a frame, a sheaf delivery member pivotally mounted thereon movable in a substantially upright plane into engagement with said frame, operating mechanism for said member with respect to 10 which the latter may move independently after it passes over its center, and supplemental means engageable with said sheaf delivery member for reducing the speed thereof as it moves downward into engagement 15 with said frame.

8. In a shocking machine, a frame, a normally prostrate sheaf delivery member pivoted thereon, mechanism for oscillating the same back and forth about its pivot, and 20 supplemental means maintaining said sheaf delivery member at a constant speed during the last stages of its return movement to sheaf receiving position.

9. In a shocking machine, a frame, a normally prostrate sheaf delivery member pivoted thereon, means for oscillating the same about its pivot, constant speed mechanism associated therewith, and means automatically connecting said constant speed mechanism with said sheaf delivery member during a predetermined range of movement of the latter.

10. In a shocking machine, a frame, a normally prostrate sheaf delivery member 35 pivotally mounted thereon movable about its axis from prostrate to inverted position, means for driving said sheaf delivery member, and constant speed mechanism automatically connected with said sheaf delivery member as the latter returns to prostrate 40 position.

11. In a shocking machine, a frame, a sheaf delivery member pivotally mounted thereon, operating mechanism therefor oscillating the same about its pivot, independently moving constant speed mechanism, and means connecting said sheaf delivery member with said constant speed mechanism during a predetermined range of movement of 50 said sheaf delivery member.

12. In a shocking machine, a frame, a normally prostrate sheaf delivery member pivoted thereon, means for oscillating the same back and forth about its pivot, supplemental constant speed mechanism operatively connected to said operating mechanism, and a clutch connecting said sheaf delivery member to said constant speed mechanism controlled by the movement of said 65 sheaf delivery member.

13. In a shocking machine, a frame, a sheaf delivery member pivoted thereon, means for oscillating the same about its pivot, supplemental constant speed mecha-

nism, and ratchet and pawl mechanism automatically thrown into operation by said sheaf delivery member and connecting the latter to said constant speed mechanism during a predetermined range of movement of said sheaf delivery member. 65

14. In a shocking machine, a frame, a sheaf delivery member pivotally mounted thereon, means for oscillating the same about its axis, constant speed mechanism comprising a sprocket having a serrated inner periphery, an arm movable with said sheaf delivery member, and a spring-pressed pawl carried on said arm and normally engaging the serrations on said sprocket. 70

15. In a shocking machine, a frame, a sheaf delivery member pivoted thereon, means for oscillating the same about its pivot, a constant speed mechanism operatively connected to said oscillating means comprising a rotating element having a serrated face, and a spring-pressed pawl movable with said sheaf delivery member engaging the serrated face on said movable element. 85

16. In a shocking machine, a frame, a normally prostrate sheaf delivery member pivotally mounted thereon, means for oscillating the same back and forth in a vertical plane, supplemental constant speed mechanism, and a clutch mechanism intermediate 95 said constant speed mechanism and said sheaf delivery member automatically connecting said sheaf delivery member to said constant speed mechanism as the former in its return movement passes from vertical to 100 horizontal position.

17. In a shocking machine, a frame, a sheaf delivery member pivotally mounted thereon, operating mechanism therefor oscillating the same back and forth in a vertical plane and allowing said member to fall freely downward in its return movement after it has passed its vertical position, and constant speed retarding mechanism for said sheaf delivery member automatically 105 thrown into train therewith moving at a slower speed than the normal speed of movement of said sheaf delivery member in passing downward from said vertical position. 110

18. In a shocking machine, a frame, a sheaf delivery member pivotally mounted thereon, means for oscillating the same in a vertical plane about its pivot, constant speed mechanism, and speed reducing mechanism comprising ratchet mechanism intermediate said constant speed mechanism and said sheaf delivery member automatically connecting said sheaf delivery member to said constant speed mechanism as the latter moves in one direction past its vertical position. 115

19. In a shocking machine, a frame, a sheaf delivery member pivotally mounted

- thereon, means for oscillating the same back and forth about its pivot, a constant speed mechanism, and means automatically connecting said sheaf delivery member to said constant speed mechanism operable when the speed of movement of said sheaf delivery member in one direction tends to exceed the speed of movement of said constant speed mechanism.
20. In a shocking machine, a frame, a sheaf delivery member pivotally mounted thereon, means for oscillating the same about its pivot, constant speed mechanism operatively connected to said oscillating means comprising a rotating element, and means automatically connecting said sheaf delivery member to said rotating element when the speed of movement of said sheaf delivery member tends to exceed the speed of movement of said rotating element.
21. In a shocking machine, a frame, a sheaf delivery member pivoted thereon, means for oscillating the same in a vertical plane about its pivot, a constant speed mechanism, and means automatically retarding the movement of said sheaf delivery member from vertical to horizontal position automatically connecting said sheaf delivery member to said constant speed mechanism when the speed of movement of said sheaf delivery member tends to exceed the speed of said constant speed mechanism.
22. In a shocking machine, a frame, a sheaf delivery member pivoted thereon, means for oscillating the same about its pivot, a constant speed mechanism operatively connected to said oscillating means comprising a rotating element having a serrated face, and a spring-pressed pawl movable with said sheaf delivery member engaging the serrated face on said movable element when said sheaf delivery member is moved in one direction at a greater speed than said rotating element.
23. In a shocking machine, a frame, a sheaf delivery member pivoted thereon, means for oscillating the same about its pivot, a constant speed mechanism operatively connected to said oscillating means comprising a rotating element having a serrated face, and a spring-pressed pawl movable with said sheaf delivery member engaging the serrated face on said movable element to limit the movement of said sheaf delivery member when the latter moves in one direction and freely movable over said serrated face when said sheaf delivery member moves in the opposite direction.
24. In a shocking machine, a frame, a shaft journaled thereon, a member rotatably mounted upon said frame, a sheaf delivery member carried upon said shaft, means for rotating said rotatable member at a constant speed, means for swinging said sheaf

65 delivery member about its pivot, and automatic connections between said sheaf delivery member and said rotating member whereby the former is automatically connected to the latter at a predetermined stage in the movement of the former.

70 25. In a shocking machine, a frame, a shaft journaled thereon, a member rotatably mounted upon said frame, a sheaf delivery member carried upon said shaft, means for rotating said rotatable member at a constant speed, means for swinging said sheaf delivery member about its pivot, and automatic connections between said sheaf delivery member and said rotating member whereby the speed of movement of the former at 75 a predetermined stage in its movement is automatically prevented from exceeding the speed of said constant speed member.

80 26. In a shocking machine, a frame, a shaft journaled thereon, a sheaf delivery member operatively connected to said shaft and rotatable therewith, a freely rotatable member carried on said frame, means for rotating said member continuously at a constant speed, means for rotating said shaft and delivery member, and means whereby said shaft and sheaf delivery member may be automatically connected with said rotatable member and driven thereby at a predetermined stage in the movement of said delivery member.

85 27. In a shocking machine, a frame, a plurality of shafts journaled thereon, a pitman connection between said shafts, a source of power, clutch mechanism controlling the 90 connection of one of said shafts and said pitman connection to said source of power, a supplemental power connection between said source of power and the other of said shafts, a sheaf delivery member operatively 95 connected to said last mentioned shaft, and means whereby upon actuation of said clutch mechanism the sheaf delivery member is rotated with its shaft and operatively connected with said supplemental power connection at a predetermined stage in its movement.

100 28. In a shocking machine, a frame, a shaft journaled thereon, a sheaf delivery member carried by said shaft, a pawl carried on said shaft, a rotating member journaled on said shaft having an internal toothed surface engageable by said pawl, means for rotating said rotatable member continuously at a constant speed, and means for moving said shaft and sheaf delivery member independently thereof.

105 29. In a shocking machine, a frame, a shaft journaled thereon, a sheaf delivery member carried by said shaft, a pawl carried on said shaft, a rotating member journaled on said shaft having an internal toothed surface engageable by said pawl,

means for rotating said rotatable member continuously at a constant speed, a coöperating power shaft carried on said frame, and resilient crank and pitman connections between the same and said first mentioned shaft.

30. In a shocking machine, a frame, a shaft journaled thereon, a sheaf delivery member carried by said shaft, a pawl carried on said shaft, a rotating member journaled on said shaft having an internal toothed surface engageable by said pawl, a constant speed source of power operatively connected to said rotating member, a coöperating power shaft carried on said frame, resilient crank and pitman connections between the same and said first mentioned shaft, and a clutch controlling the connection between said coöperating power shaft and said source of power.

31. In a shocking machine, a frame, a shaft journaled thereon, a sheaf delivery member carried by said shaft, a radially extending arm carried on said shaft, resilient means on said frame compressible by said arm in a predetermined position of said delivery member, a rotatable member journaled on said frame having an inner toothed surface, a pawl pivotally mounted on said arm and engageable with said toothed surface, means for rotating said rotatable member at a constant speed, and means for moving said shaft and sheaf delivery member independently thereof.

35. 32. In a shocking machine, a frame, a shaft journaled on said frame, a sheaf delivery member carried on said shaft, a sprocket journaled on said shaft having an inner serrated surface, a radially extending arm carried on said shaft, a spring pressed pawl carried on said arm engageable with the serrated surface of said sprocket, means intermediate said arm and frame compressible by said sheaf delivery member and limiting the movement of the same, a coöperating shaft journaled on said frame, resilient pitman connections between the same and said first mentioned shaft, a sprocket on said coöperating shaft, a clutch controlling the connection of said sprocket to said shaft, a power shaft journaled on said frame, a sprocket on said power shaft, and a single chain operatively connected between said sprocket and the sprockets on said first mentioned shafts.

to said shaft, a power shaft journaled on said frame, and means operatively connected thereto for rotating said sprockets.

33. In a shocking machine, a frame, a shaft journaled on said frame, a sheaf delivery member carried on said shaft, a sprocket journaled on said shaft having an inner serrated surface, a radially extending arm carried on said shaft, a spring pressed pawl carried on said arm engageable with the serrated surface of said sprocket, means intermediate said arm and frame compressible by said sheaf delivery member and limiting the movement of the same, a coöperating shaft journaled on said frame, resilient pitman connections between the same and said first mentioned shaft, a sprocket on said coöperating shaft, a clutch controlling the connection of said sprocket to said shaft, a power shaft journaled on said frame, and means operatively connected thereto for rotating said sprockets at a constant speed.

34. In a shocking machine, a frame, a shaft journaled on said frame, a sheaf delivery member carried on said shaft, a sprocket journaled on said shaft having an inner serrated surface, a radially extending arm carried on said shaft, a spring pressed pawl carried on said arm engageable with the serrated surface of said sprocket, resilient means intermediate said arm and frame compressible by said sheaf delivery member and limiting the movement of the same, a coöperating shaft journaled on said frame, resilient pitman connections between the same and said first mentioned shaft, a sprocket on said coöperating shaft, a clutch controlling the connection of said sprocket to said shaft, a power shaft journaled on said frame, a sprocket on said power shaft, and a single chain operatively connected between said sprocket and the sprockets on said first mentioned shafts.

In testimony whereof I affix my signature, in the presence of two witnesses.
